(57) **CLAIM**

The ornamental design for a cutlery fork, as shown and described.

DESCRIPTION

FIG. 1 is a right side perspective view of a cutlery fork showing my new design;

FIG. 2 is a first end view of the cutlery fork of FIG. 1;
FIG. 3 is a left side elevation view of the cutlery fork of FIG. 1;

FIG. 4 is a right side elevation view of the cutlery fork of FIG. 1;

FIG. 5 is a second end view of the cutlery fork of FIG. 1;
FIG. 6 is a top plan view of the cutlery fork of FIG. 1;
FIG. 7 is a bottom plan view of the cutlery fork of FIG. 1; and,
FIG. 8 is a bottom, and right side perspective view of the cutlery fork of FIG. 1.

The handle of the cutlery fork is shown in broken lines for illustrative purposes only and forms no part of the claimed design.

1 Claim, 8 Drawing Sheets
